UNITED STATES PATENT OFFICE

JOSEPH W. GOSLING, OF SCHENECTADY, NEW YORK, ASSIGNOR TO GENERAL ELECTRIC COMPANY, A CORPORATION OF NEW YORK

DESIGN FOR AN ELECTRIC FAN

Application filed December 1, 1932. Serial No. 46,272. Term of patent 14 years.

To all whom it may concern:

Be it known that I, JOSEPH W. GOSLING, a citizen of the United States, residing at Schenectady, in the county of Schenectady, State of New York, have invented a new, original, and ornamental Design for an Electric Fan, of which the following is a specification, reference being had to the accompanying drawing, forming a part thereof.

In the drawing, Fig. 1 is a front elevation of the electric fan showing my new design and Fig. 2 is a side elevation.

I claim:

The ornamental design for an electric fan as shown.

In witness whereof, I have hereunto set my hand.

JOSEPH W. GOSLING.
